[57] ABSTRACT

A hopper car including a plurality of longitudinally spaced discharge openings forming a trough type discharge arrangement having converging slope sheets which provide a plurality of spaces separating the discharge openings. A discharge gate arrangement includes a closure gate for each of the discharge openings, the gate comprising a plurality of individual sections which are sequentially movable into the spaces between the discharge openings to an out-of-the-way open position with the sections vertically stacked within said spaces. The spaces provided between the discharge openings also support, on a frame structure therein, rotatable shafts including reel means or pulley arrangements about which chains are trained, the said chains being connected to one of the gate sections for sequentially moving the sections between the open and closed positions. Another shaft is positioned adjacent each opening provided at opposite ends of the car to which the chains of one of the pulleys within the space are connected for operating the movement of the discharge gates. During the opening of each gate, the shaft is rotated so that the chain winds around the pulley and during the initial opening a high torque is exerted on the first gate section to move the same and the speed of the initial movement is comparatively slow. As the chain further winds onto the pulley, the gate sections are moved more rapidly and less torque is exerted by virtue of the chain winding. The converse is achieved when it is desired to close the gate; the other cooperating shaft and pulley initially exert a high operating torque to move the first section of the gate and as the chain winds about the last mentioned pulley the diameter increases lessening the torque and increasing the speed of operation.

CHAIN ACTUATED RAILWAY HOPPER GATE

SUMMARY

The present invention is an improvement over applicant's patent application, Ser. No. 801,634, filed Feb. 24, 1969, now abandoned, and is also an improvement over applicants' continuation-in-part patent application, Ser. No. 39,682 filed May 20, 1970.

A prime object of the present invention is to provide an improved gate arrangement for a plurality of discharge openings of a hopper car forming a trough type of discharge arrangement wherein each of the gates for the arrangement includes the advantages of high torque in initially breaking the gates loose from the closed position and thereafter increasing the speed of movement with a lesser torque. The present invention contemplates a plurality of discharge openings each having a sectional type of discharge gate which is actuated by operating shafts rotatably positioned on opposite longitudinal ends of the discharge opening and which include reel or pulley type members on which a chain is connected, the said chain being connected to one of the sections of a sectionalized gate arrangement. As one shaft and pulley arrangement winds up the chain thereon, the other unwinds thus affording extremely high torque application at the initial opening or closing of the gate and subsequently as the gate is being moved, the speed increasing. Therefore, the prime object of a high speed and high torque gate operating mechanism is achieved by the present invention.

BRIEF DESCRIPTION OF THE DRAWINGS

FIG. 1 is a side elevational view of a railway hopper car;
FIG. 2 is a plan view of a discharge gate arrangement for one of the discharge openings of a railway hopper car;

FIG. 3 is a cross-sectional view taken substantially along the line 3-3 of FIG. 2, also disclosing portions of a hopper arrangement;

FIG. 4 is a side elevational view of the gate arrangement taken substantially along the line 4-4 of FIG. 2, with certain portions broken away;

FIG. 5 is a cross-sectional view showing a pair of gate sections in overlapping relation including sealing means at a rear end of one of the sections and cooperating seal means at the forward end of another gate section;

FIG. 6 is a cross-sectional view taken along the line 6-6 of FIG. 5;

FIG. 7 is a cross-sectional view taken substantially along the line 7-7 of FIG. 2; and

FIG. 8 is a cross-sectional view taken substantially along the line 8-8 of FIG. 3.

DETAILED DESCRIPTION

Referring now particularly to FIG. 1, a railway hopper car 10 includes a body generally designated 11 and at opposite ends thereof includes a suitable underframe structure provided with center sill sections 12. Conventional trucks 13 support the center sills 12. The body 11 includes a plurality of hoppers 14 provided by vertically extending side sheets or walls 15 suitably connected to transversely extending end slope sheets 16. The hopper car 10 is provided with a trough type discharge arrangement which is formed of a plurality of intermediate slope sheets 17 of inverted V-shaped configuration which between the hoppers provide a space 18. The intermediate slope sheets 17 provide, as in the present case, three discharge openings designated at A. A lesser or greater number of such openings A can of course be provided depending upon the length and size of the railway hopper car.

The openings A are controlled by a discharge gate and frame arrangement generally designated 19. The gate and frame arrangement 19 includes at opposite ends of the body 11 transversely extending vertical walls 20. Each of the intermediate slope sheets 17 which diverge downwardly are connected to a transversely extending angle wall member 21 as

best shown in FIG. 4. Thus, each opening A is provided at its ends with either a vertical wall 20 or an angle wall member 21, the latter being connected to each of the diverging intermediate slope sheets 17. As best shown in FIGS. 1 and 2, the gate and frame arrangement 19 also includes a pair of longitudinally extending and laterally spaced side wall members 22 which are connected to the opposite ends of the walls 20 and 21. The vertical wall members 20 are provided with flared edges 23 which are suitably connected to the end slope sheets 16, as best shown in FIG. 3. The upper ends of the longitudinal wall members 22 also are provided with flared edge portions 24 which are suitably connected to the lower ends of the side sheets 15 which also slope downwardly and inwardly to form the discharge openings A. Opposite ends of the longitudinal members 22 are interconnected by transversely extending angle cross members 25, only one of which is shown in FIGS. 2 and 3. The angles 25 are connected to the longitudinal wall members 22 by vertical extensions 26.

As best shown in FIG. 8, the longitudinal wall members 22 are provided with inwardly directed ledges 27, 28, 29 and 30. As best shown in FIG. 7, the vertical walls 20 are also provided with a longitudinal inwardly turned ledge 31. The ledges 27, 28, 29 and 30 respectively support gate sections 32, 33, 34 and 35 in sliding movement between the longitudinal wall members 22. The lower ledge 27 which supports the lower gate section 32 extends completely the length of the discharge opening A since the distance of travel of the section 32 is throughout the whole length of the opening. It must be realized that the ledges 28, 29 and 30 for supporting the gate sections 33, 34 and 35 need only extend longitudinally within the opening to the farthest position of travel of each section as shown in FIG. 3. As best shown in FIG. 7 the wall sections 20 also are provided with inwardly directed tabs or projections 36 which maintain the gate section 27 against vertical displacement. In the present disclosure four sections are provided for a single gate to close the discharge opening A. As best shown in FIG. 5, the sections are disposed in overlapping vertically spaced relation, the leading edge of one section overlapping the trailing edge of another.

In FIG. 5 the trailing section of the gate 32 is provided with a flat bar 37 which extends across the width of the gate 32 and has connected thereto, and coextensively therewith, a sealing strap 38 which may be of suitable sealing material. The leading edge of the next gate section 33 above is provided with a laterally extending flat bar 39 which has connected thereto on the underneath side thereof, coextensively, a strap 40 also of suitable seal material which when the gates are placed in the sealing relation shown in FIG. 5, the said sealing edges overlap one another to provide an effective seal. Sections 34 and 35 are similarly interconnected and have their overlapping edges sealed. At the sealing points of the overlapping gate sections, a wedge tab 41 is also provided, these tabs 41 as best shown in FIG. 2, being inclined downwardly to be engaged by the leading edge portions of the gates 33 and 35, which as the gate sections are forced into the closed overlapping position, provide for effective sealing of the overlapping leading and trailing edges of the cooperating gate sections.

It is, of course, understood that FIG. 2 shows only one side of one of the gate arrangements but that the arrangements are symmetrical. Each of the gates for each discharge opening is actuated by means of transversely positioned shafts 42 and 43 which are rotatably connected and supported on the vertical extensions 26. The actuating shafts 42 and 43 also have connected thereto operating heads 44 shown in FIG. 2 which may be conventional and suitably engaged by an operator with a suitable tool for rotating said shafts. Pulleys or reel means 45 are fixed on the shafts 42 and pulleys 45' are fixed on shafts 43, said pulleys being disposed on opposite ends of the longitudinal members 22. A chain 46 is suitably connected as indicated at 47 to the pulleys 45 and 45' with said chain extending alongside the longitudinal members 22 adjacent the said opening. The lowermost section 32 of each of the gates is also provided with downwardly extending bracket members 49 to

which each chain 46 is connected by means of a connection 50. As best shown in FIGS. 2 and 4, the sections 33, 34, and 35 are also provided at their trailing edges with stop members 48 projecting downwardly. The section 35 is further provided, as shown in FIG. 4, with a transversely extending sealing strip 51, which in the closed position of section 35 suitably seals one end of the discharge opening A.

THE OPERATION

Referring not particularly to FIGS. 2 and 3, the operation of one of the sectional gate arrangements for one of the discharge openings A will be described. The shaft 43 is rotated to operate the pulleys 45' to move the same in a clockwise direction whereupon the chain 46 is wound upon the pulleys 45'. Simultaneously the shaft 42 is rotated in a clockwise direction and the chain thereon is unwound from pulleys 45. Movement of the chain 46 longitudinally moves the bracket 49 and the lower section 32 to which it is connected in a rearward manner. At this initial movement the chain is wound around the lowest diameter portion of the pulleys 45' and a large torque is thus achieved in breaking the first section 32 loose from its closed relation. This is particularly desirable in certain types of material which, in the case of a non-sequential movable gate, makes it virtually impossible to open the gate manually. Because of the high torque effectuated initially by the winding of the chain 46, the gate section 32 is broken free from the closed position. The gate section 32 as shown in FIG. 3, moves to the left and the trailing edge of said gate engages the stop 48 of the next uppermost gate section 33 in turn causing the said gate section to move rearwardly further opening the opening A. The gate sections 34 and 35 are similarly sequentially moved as the stops 48 are engaged by the trailing edge of the immediately lower gate section until the sections are all disposed as shown in FIG. 3 in the space 18 which is provided.

During closing of the gate as shown in FIGS. 2, 3, and 4, the pulleys 45 are moved in a counterclockwise direction whereupon the chain 46 is unwound from the pulleys 45' which also moves counterclockwise and the chain 46 is wound upon the pulleys 45. Initially, high torque is effectuated to start closing the gate which is desirable if the discharge opening has material flowing therethrough of a relatively dense character but as the gate continues to further close it speeds up since as the chain 46 winds upon itself greater speed and less torque is effected. The same of course is true during closing in that a higher speed of operation is obtained as the gate sections are moved toward their closed position. As the first gate section 32 moves across the opening A, its trailing edge and flat bar 37 and seal 38 engage the flat bar 39 and seal 40 of the immediately upper section 33 which then causes movement outwardly from the space of the said section 33 and the same operation continues with respect to sections 34 and 35 until the section 35 is in the closed position shown in FIG. 4; the leading section 32 is in the position shown in FIG. 7 and the gate is completely closed.

In the spaces shown in FIG. 1, the shafts 43 operate to open the gate whereas the shafts 42 are operative to close the gate. The arrangement of course may be changed as desired, it being desirable of course to store the sections within the spaced 18 provided where they are in an out-of-the-way protected position. In the arrangement shown in FIG. 1, storage for the gates is provided in spaces 18 wherein they are fully protected and out of the way with respect to other portions of the hopper car.

Thus it is believed that the object of the invention has been fully achieved. It is believed that various changes in the arrangement may be made and these are contemplated and within the scope of the present invention.

What is claimed is:

1. A gate mechanism for controlling the discharge of materials through the discharge opening of a hopper comprising:

a frame having laterally spaced longitudinal side walls and longitudinally spaced end walls connected to said side walls,
said frame being connected to said hopper beneath said discharge opening,
said side walls including extensions projecting longitudinally outwardly on opposite ends of said discharge openings, a closure gate carried by said side walls slidably movable to a position closing said discharge opening and to an open position carried on said projecting extension, means for moving said gate between said positions including first and second laterally extending rotatable shafts respectively carried one on each of said extensions longitudinally outwardly opposite said end walls, said shafts having respectively carried thereon first and second pairs of pulleys, a pair of flexible elements having first ends connected to said first pulleys and second ends connected to said second pulleys, and means connecting said flexible elements to said closure gate whereupon during rotating movement of said shafts, certain portions of said flexible elements are wound upon themselves about one pair of said pulleys and other portions of said flexible elements are simultaneously unwound from said other pair of pulleys whereby portions of said flexible elements move longitudinally to move said gate with maximum torque at a low speed during initial movement of the gate and decreasing torque and increasing speed with continued movement of the gate.

2. A railway hopper car including a plurality of longitudinally spaced hoppers each having longitudinally spaced downwardly converging walls providing at their lower ends a plurality of discharge openings at least two adjacent discharge openings having said converging walls associated to provide a space between and underneath said hoppers separating said discharge openings, the improvement comprising:

a closure gate assembly for each said hopper, each said assembly including a frame having interconnected vertical walls disposed about a respective discharge opening,

a closure gate slidably supported on each said frame for longitudinal movement,

each said gate including a plurality of sections relatively movable with respect to each other and being supported on said frame in relatively superposed relation,

a rotatable member fixedly supported on each end of each of said frames with at least one of said members being within said space,

a flexible element having one end connected to each of said rotatable members and an intermediate portion connected to said gates,

said rotatable members being adapted to be rotatably driven to wind said flexible element upon itself on one of said members while simultaneously unwinding it from the other of said members thereby sliding said sections on said frame to move said gates between open and closed positions, at least one of said gates having its sections disposed in said spaces in the open position, with each of the sections being disposed one above the other in relatively vertical stacked arrangement.

3. The invention in accordance with claim 2, said rotatable members including shafts having winding reels connected thereto upon which said flexible elements are wound.

4. The invention in accordance with claim 3,

said flexible elements being wound upon themselves and initially, during winding, providing a maximum torque for opening of said gate at a certain speed and said torque decreasing and said speed increasing as said flexible elements are wound about themselves.

5. The invention in accordance with claim 4, said flexible elements comprising a link chain.

6. A gate mechanism for controlling the discharge of materials through the discharge opening of a hopper, comprising:

a frame including vertical walls interconnected below and extending about said discharge opening,
 a closure gate carried by said frame and slidably movable from a closed position over said discharge opening to an open position to one side of said opening,
 a first shaft including reel means carried thereby on said frame on same side of said opening,
 a second shaft including second reel means carried thereby on said frame on an opposite side of said opening,
 chain means having one end connected to each of said reel means and an intermediate portion connected to said gate, said chain means being adapted to be wound upon itself during rotation of said shafts and reel means whereby during initial movement of said gate a maximum torque is provided at a certain speed of movement of said gate and said torque decreasing and said speed increasing as said chain means is wound upon itself.

7. The invention in accordance with claim 6,
 said gate including sections disposed on said frame in vertically spaced and longitudinally disposed relation, and in the open position being stacked one above the other to one side of said discharge opening.

8. A gate mechanism for controlling the discharge of materials through the discharge opening of a hopper, comprising:

a frame including vertical walls interconnected below and extending about said discharge opening,
 a closure gate carried by said frame and slidably movable from a closed position over said discharge opening to an

5

10

15

25

open position to one side of said opening,
 a first shaft including reel means carried thereby on said frame on same side of said opening,
 a second shaft including second reel means carried thereby on said frame on an opposite side of said opening,
 chain means having one end connected to each of said reel means and an intermediate portion connected to said gate and adapted to be wound upon one said reel means and upon itself during driving rotation of one said shaft whereby said gate is moved in one direction and during which movement said chain means is unwound from said other reel means,
 and being wound upon said other reel means and upon itself during driving rotation of said other shaft to move said gate in an opposite direction during which movement said chain means is unwound from said other reel means, whereby

a high torque at low speed is exerted during initial opening or closing movement of said gate and a higher speed of movement and lower torque is exerted as said gate moves closer to it open or closed position.

9. The invention in accordance with claim 8,
 said gate comprising a plurality of sections disposed on said frame in vertically spaced relation, being sequentially movable to a closed position and being stacked one above the other on said frame to one side of said discharge opening.
